assignors to Industrial Patents Corporation,
Chicago, Ill., a corporation of Delaware

Application May 26, 1934, Serial No. 727,620

5 Claims. (CL 62—91.5)

This invention relates to improvements in insulated containers adapted for the shipment of food products under refrigeration.

One of the objects of this invention is to provide an efficient, inexpensive insulated container of the returnable type, especially adapted for express shipments of food products and for use on unrefrigerated trucks.

Another object of this invention is to provide a collapsible container of this type.

An important object of the invention is to provide a means whereby more perishable products such as fresh meat cuts, frozen meats, sweet pickle meats, cheese, butter and the like may be adequately protected with solid carbon dioxide when shipped in a refrigerator car loaded with less perishable products requiring less refrigeration.

Another object of the invention is to provide a refrigerator package to insure protection for highly perishable items when shipped in poorly insulated refrigerator trucks.

Other objects of the invention will be apparent from the description and claims which follow.

It will be seen that the present invention provides a novel container of the type described and also provides a novel, economical method of packing and shipping highly perishable foodstuffs.

The highly perishable products such as fresh meats, frozen meats, sweet pickle meats, cheese, butter and the like constitute a relatively small proportion of the product ordinarily shipped in packer refrigerator cars. In an average car of this type carrying from 30,000 to 35,000 pounds of product, not more than 5,000 to 10,000 pounds would be considered highly perishable, the balance consisting of smoked meat, summer sausage, soap and other relatively less perishable merchandise.

If the highly perishable product is segregated and independently refrigerated it can be ignored in the consideration of the necessary refrigeration for the bulk of the car load. In accordance with the present invention the highly perishable product is packed in sealed containers refrigerated with solid carbon dioxide, and consequently during the major portion of the year it is unnecessary to ice packer refrigerator cars. Furthermore, in the summer the less perishable product can be adequately protected by icing the cars without salt and eliminating the necessity which otherwise would exist for re-icing.

In the accompanying drawings similar reference characters indicate similar elements in the several figures.

Figure 1 is a perspective view of a collapsible container constructed in accordance with the

present invention with the end pieces removed to show the inside construction.

Figure 2 is a fragmentary sectional view showing one end piece.

Figure 3 is a sectional view through the side walls of the container shown in Figure 1.

Figure 4 is a sectional detailed view of a corner of the side walls.

Figure 5 is a perspective view of the container as it appears when completely closed.

Figure 6 is a sectional view showing the container packed with packaged goods.

Figure 7 is a sectional view showing the container packed with divers loose items of irregular contour.

Figure 8 is a view partly in section showing the container packed with bone-in meat cuts and packaged goods, as used in a refrigerator car.

The embodiment of the invention shown in the drawings is constructed of substantially rigid insulating material, preferably about two inches thick, designated as 1, covered with sheet metal 2 on the outside and inside. The side walls 3 are hinged to each other with piano type hinges 4. The sheet metal covering the outer surfaces of the side walls 3 extends beyond the end of the insulating material as at 5, forming a ledge or recess in which ends 6 may be nested. The outside of the container is covered with fabrics such as canvas 7 with flaps 8 to lap over the ends. Straps 9 are provided to secure flaps 8 in the manner shown in Figure 5. Figure 4 illustrates the manner in which the sheet metal is secured to the insulating material as by nails 10.

It will be noted by reference to this figure that the sheet metal on the outside does not meet at the edges of adjacent sides and there is therefore no interference with collapsing. When the container is packed, liver racks 11 are inserted against the sides and the bottom to insure free circulation of air around the product.

In Figure 6, for example, a liver rack is placed on top of the packaged product 12, and solid carbon dioxide blocks 13 fastened on top of the top rack. Where loose meat 14 is packed as shown in Figure 7, several thicknesses of heavy paper 15 as "Kraft" paper is utilized to prevent contact of the meat with the racks, and layers of meat are separated by one or more thicknesses of the same material.

Figure 8 discloses the manner of loading the container with bone-in meat cuts 15 suspended from conventional meat hooks 16 which pass through openings in the top of the container and are suspended from the conventional rails 56

in the refrigerator car or truck. The openings through which the meat hooks pass are preferably protected with fabric or metal flaps to cut down loss of refrigeration.

5 5. Packaged goods 12 may be packed in the bottom of the container to economize on space. Where desired, very low temperatures may be secured in the container by using larger quantities of solid carbon dioxide than is necessary to carry the temperature low enough to be satisfactory for unfrozen meats.

10 We claim:

15 1. A collapsible refrigerator container comprising hinged insulated side walls protected with sheet metal on the inner and outer surfaces and removable insulated sheet metal covered end pieces, racks within said container adjacent the sides and bottom to provide air circulation and a rack near the top within said container adapted to carry an anhydrous refrigerant, a cover for said container and means for closing said cover.

20 2. A collapsible refrigerator container comprising hinged insulated side walls protected with sheet metal on the inner and outer surfaces and removable insulated sheet metal covered end pieces, racks within said container adjacent the sides and bottom to provide air circulation and a rack near the top within said 25 container adapted to carry an anhydrous refrigerant, a cover for said container and means for

30 closing said cover, openings in the top of said container to accommodate suspension hooks and means for protecting said openings against refrigeration loss.

3. The method of hanging meat cuts in a refrigerated vehicle which comprises suspending the meat cuts within a refrigerated container maintained at a lower temperature than the main body of the refrigerated vehicle, said meat cuts depending from suspension hooks carried by an overhead support exteriorly of said refrigerated container.

4. A collapsible refrigerator container comprising hinged insulated side walls, removable insulated end pieces, racks within said container adjacent the sides and bottom to provide air circulation, a rack near the top within said container, a cover for said container and means for closing said cover.

5. A collapsible refrigerator container comprising hinged insulated side walls, removable insulated end pieces, racks within said container adjacent the sides and bottom to provide air circulation, a rack near the top within said container, a cover for said container, means for closing said cover, openings in the top of said container to accommodate suspension hooks and means for protecting said openings against refrigerating loss.
